APPARATUS FOR DISPENSING SEALING STRIPS OR THE LIKE

John D. Nixon, Laleham-on-Thames, England, assignor of one-half to Areenco Limited, London, England, a British corporation

Application February 19, 1954, Serial No. 411,516

Claims priority, application Great Britain
February 20, 1953

1 Claim. (Cl. 271—2.4)

The present invention relates to an apparatus for dispensing sealing strips or the like which may consist of paper, plastic material or another thin and flexible material. Such apparatus are commonly used for the delivery of sealing strips for packages which are advanced successively whereby an adhesive tape of paper or the like is unwound from a roll and moistened and cut into strips above the package to the sealing end of which the operator then attaches and smooths the adhesive strip manually.

The gummed side of the tape should not, after the moistening, come into contact with any other member of the machine nor the operator's hands. Since the flat band, especially after it has been moistened, is very flexible and likely to bend it is, however, in the use of apparatus of the kind hitherto known, difficult or impossible to overcome said drawback unless the apparatus has a pincher which grips the free end of the tape and draws it to the required position and then releases it. Thereby the gripper will, however, be sticky or it will prevent the moistening of the end of the tape and, furthermore, it will get in the way of the operator.

Said inconveniences are overcome by the present invention. Thus, the cut strip will without the aid of any gripping device and without bending be fed to the sealing position even though it has then been moistened along its entire length, that is, from the edge of one of its ends to the edge of the other end so that it will also at its ends be effectively and smoothly applied adhesively to the package. The operator's hands will not come in contact with the sticky side of the tape and the frequent washing of hands hitherto necessary in manual sealing operations will not be required.

Thus, the apparatus has, according to the invention, a forming or shaping device located in the path of travel of the tape and adapted to impart to the tape a substantially curved profile by bending it, that is to say, creasing it longitudinally. Said forming or shaping device may consist of two co-operating rollers, one of which has a convex or wedge-shaped profile, while the other has a concave or channel-shaped profile, the concave or channel-shaped profile being conveniently somewhat flatter than the convex or wedge-shaped profile. Thus, as the tape advances between said forming rollers it is bent and creased longitudinally into an upwardly concave trough extending in the direction of advance.

In the accompanying drawing, which illustrates the invention by way of example, Fig. 1 is an elevational view of the front side of the apparatus and Fig. 2 is an elevational view of its rear side. Fig. 3 shows a vertical section on the line III—III of Fig. 2. Figs. 4 and 5 are elevational views on the lines IV—IV and V—V, respectively, of Fig. 1.

The gummed tape B is unwound from a roll 1 and conveyed around a guide roller 2 and over a guide roller 3 and further between two rollers 4 and 5 and thereafter past a guillotine 6 and a tape moistening brush 7.

The rollers 4 and 5 act as feed rollers as well as a

2

tape forming or shaping device. The upper roller 4 has a wedge-shaped profile (Fig. 3) and the profile of the lower roller 5 is channel-shaped or V-shaped with a somewhat larger angle than the roller 4. The roller 4 is secured to a shaft 57 which is rotatably mounted in a block 56 and to which is secured a gear wheel 8 which meshes with a gear wheel 9. The gear wheel 9 is secured to a shaft 10 which is parallel to and positioned right below the shaft 57 and rotatably mounted in a boss 11 on the frame 17. On the shaft 10 are rotatably mounted a pinion 12 and an arm 13 secured to the latter. To the arm 13 is pivoted a pawl 14 which engages yieldingly a ratchet wheel 15 secured to the shaft 10. The pinion 12 meshes with a toothed segment 18 rotatably mounted on a pin 16 in the frame 17 and connected to an arm 20 by means of a link 19. The arm 20 is by means of a tension spring 47 connected to the frame 17 and pivoted to a pin 21 in the frame 17 and it has a roller 37 engaging a cam 22 which is secured to a drive shaft 23 mounted on the frame 17.

The block 56 is slidably mounted in a vertical guide 24 in the frame 17. A manually operable nut 25 is with a slight vertical play inserted in an upper portion 26 of the guide 24. Into the nut 25 is inserted a screw 27 which has an annular flange 28 which constitutes an upper shoulder engaging a helical compression spring 29 the bottom end of which abuts the block 56 so that it urges the roller 4 against the roller 5 with a pressure depending on the setting of the nut 25.

Behind the rollers 4, 5, that is, further on in the tape feeding direction, there is a guide block 30 secured to the frame 17 and having a concave profile which to a certain degree corresponds to the profile of the roller 5. Upon the guide block 30 is yieldingly positioned another block 30a having at its lower side a convex profile adapted to the concave profile of the block 30 so that a shallow U-shaped guide slot 52 (Fig. 4) for the tape can be formed between both the blocks. Behind the block 30, that is, further on in the tape feeding direction, is the guillotine 6 positioned which contacts with an end portion 31 of the block 30 constituting a ledger member. Further on in the tape feeding direction the brush 7 is arranged on a water container 46 secured to the frame 17. The brush 7 has, according to Fig. 5, the same profile as the guide block 30 (Fig. 4).

The guillotine 6 has two downwardly extending arms 55 by means of which it is by a pair of tension springs 32, secured to the block 30, held in engagement with the ledger member 31 and its edge 33 has an inverted V-shape (Fig. 4). The guillotine 6 is at a pin 34 pivotally connected to an arm 35 pivoted to a pin 48 in the frame. A tension spring 36 secured to the frame 17 has a tendency to swing the arm 35 upwardly and hold it in engagement with an arm 38 which is secured to a spindle 39 rotatably mounted in the frame 17. The upward swing of the arm 38 is limited by an abutment 51 on the frame. To the spindle 39 is secured another arm 40 which by means of a link 41 is connected to an arm 44 rotatably mounted on a pin 42 in the frame. To the pin 42 is pivoted another arm 43 which under the influence of a blade spring 53 on the arm 44 is held in engagement with a shoulder 54 on the arm 44. The joint between the arms 43 and 44 will consequently form a toggle point at which the arm 43 can swing upwardly relative to the arm 44.

In the operation of the apparatus the continually revolving shaft 23 and the spring 47 reciprocate the toothed segment 18. When the toothed segment occupies the position shown in Fig. 2 the guillotine 6 is held in the raised position shown in Fig. 4. When the toothed segment is swung in the direction 6 (Fig. 2) it will by

means of its roller 45 swing the arm 43 so that the guillotine C is moved downwardly and cuts a length of strip off the tape B fed over the brush 7. Since the cutting edge 33 and the ledger member 31 converge towards the sides of the block 30 (Fig. 4) the V-shaped cutting edge 33 will obviously commence the cutting at both the longitudinal edges of the transversely bent tape B and the cut will proceed inwardly towards the center of the tape whereby the cutting will be facilitated. During the swing of the segment 18 in the direction C the pinion 12 and the arm 13 with its pawl 14 will be driven in a counterclockwise direction (Fig. 2) so that the pawl slides over the teeth of the ratchet wheel 15. Thereby the roller 45 will be moved past the free end of the downwardly deviating arm 43 and then the spring 36, having been tensioned during the downward movement of the guillotine 6, will return the guillotine to its top position.

When the toothed segment 18 is swung back in the direction F into the position shown in Fig. 2 the roller 45 is moved past the arm 43 thereby yielding upwardly and the pinion 12 with the arm 13 and the pawl 14 are driven in a clockwise direction. Thereby the pawl 14 drives the ratchet wheel 15 to rotate the shaft 10 and the gear wheel 9 in a clockwise direction (Fig. 2) so that the rollers 4 and 5 will be driven in the directions of the arrows shown in Fig. 1. Thereby the tape B is advanced through one step whereby the rollers 4 and 5 bend and crease the tape longitudinally into the V-shaped profile and the tape is moved between guide members, and then with its convex gummed side downwardly over the moist brush 7 whereby a considerable length of the tape having been reinforced by its transverse curvature and its longitudinal

crease can, without bending, protrude freely above a package onto which it is applied as a sealing strip after having been cut off in the manner described.

I claim:

5 In a tape dispensing apparatus, a lower tape shaping roller provided with an annular peripheral groove, having a sharp angle at its center, an upper tape-shaping roller having a peripheral portion of substantially wedge shape in cross section and projecting into said groove of said lower roller, the angle of the wedge of said upper roller being slightly sharper than the angle of said groove, and said rollers providing between themselves a thin but laterally widening crooked slit for the tape advancing therebetween so that the apex of the wedge of said upper roller presses the portion of the tape passing therebeneath against the bottom of said groove of the bottom roller more forcefully than the rest of said tape is pressed to bend said most strongly pressed portion of said tape sharply and crease it into a V-shaped trough extending 10 longitudinally of said tape.
